[57] ABSTRACT

A tobacco pipe having an elongated recess in the lower portion of the stem is combined with a ferromagnetic tobacco tamper and bowl scraper. A further recess is provided intermediate the elongated recess and a permanent magnet is placed therein so as to hold and retain the tamper and scraper in the elongated recess when not in use.

SMOKING PIPE WITH TOOL

This invention relates to an improved smoking pipe especially designed for ease of the cleaning and tobacco packing operations inherent in readying a pipe for smoking, by incorporating into the pipe stem a bowl cleaning and packing tool that can scrape the bowl clean after a smoke is completed and also pack a new load of tobacco. Prior to smoking and such that this tool is held in its cavity by a magnet.

The primary object of this invention is to provide a pipe with a built-in, convenient and readily available tool for cleaning the bowl of old tobacco ash and for correctly packing the new load of tobacco by having this tool incorporated directly into the pipe stem.

Still a further object of this invention relates to the ease of storing and removing this bowl cleaning and packing tool from its cavity in the stem of the pipe with the aid of a magnet in the cavity.

Various other objects and advantages of the invention will hereinafter become more fully apparent from the following description of the drawing, illustrating a presently preferred embodiment thereof, and wherein:

FIG. 1 is a perspective view of the bowl cleaning and packing tool.

FIG. 2 is a longitudinal sectional view of the complete smoking pipe with the bowl cleaning and packing tool.

FIG. 3 is a bottom view of the complete smoking pipe with the bowl cleaning and packing tool.

Referring more specifically to the drawings, the pipe consists of the bowl 2 which has a tobacco receiving cavity 1 for holding the tobacco. The bowl 2 is attached to the stem 3, attached to the stem 3 is the mouthpiece 4. The tobacco receiving cavity 1 of the bowl 2 is connected by the inside passageway 5 which passes through the stem 3 and the mouthpiece 4. This passageway 5 carries the smoke from the tobacco receiving cavity 1 to the smoker's mouth. The bowl 2 and the stem 3 are fabricated of briarwood or other suitable conventional material by conventional means. The

5 mouthpiece 4 is of plastic and made by conventional means.

A cavity 6 is cut or formed into the stem 3 by conventional means. Into this cavity 6 is placed a magnet 7 which is held in its position in this cavity 6 by an adhesive or other conventional means.

Next into the cavity 6 is placed the bowl cleaning and packing tool 8 which has two ends. The scraping end 9 is used to clean the inside wall and the bottom of the

10 bowl 2 after the pipe is smoked, and also used to remove lumps of burned and unburned tobacco that is inside the bowl 2 after smoking. The packing end 10 is used to pack the new tobacco in the bowl 2 to the proper density for a correct burning of this tobacco

15 when the pipe is smoked. At the packing end 10 of the bowl cleaning and packing tool 8 is a knurled area 11, which when the tool 8 is inserted in the cavity 6, can be pressed with the finger to partially remove the tool 8 from the magnet 7 and the cavity 6 so that a smoker's

20 finger or fingernail can be inserted under the cleaning end 9 of the tool 8 so that the tool 8 can be removed from the stem 3 and put into use. This bowl cleaning and packing tool 8 is made of chrome-plated steel by conventional means.

25 Various modifications and changes are contemplated and may be resorted to, without departing from the function or scope of the invention as hereinafter defined by the appended claim.

I claim as my invention:

30 1. A tobacco pipe having a vertically arranged bowl and a stem extending laterally from the lower end portion thereof, the stem having a first recessed portion extending lengthwise along the periphery of the lower portion thereof and arranged to receive a ferromagnetic tobacco tamping and bowl scraping tool therein, means providing a further recessed portion smaller in length than and substantially in the midportion of said first recessed portion, and a magnet mounted in said further recessed portion, said magnet being arranged to releasably hold said tool in said first recessed portion.
